UNITED STATES PATENT OFFICE.

WALTER E. DEMPSEY, OF CRAIG, NEBRASKA.

DESIGN FOR A REPAIR-BUCKLE.

57,591.

Specification for Design. Patented Apr. 26, 1921.

Application filed September 13, 1920. Serial No. 410,017. Term of patent 3½ years.

To all whom it may concern:

Be it known that I, WALTER E. DEMPSEY, a citizen of the United States, residing at Craig, in the county of Burt and State of Nebraska, have invented a new, original, and ornamental Design for Repair-Buckles, of which the following is a specification, reference being had to the accompanying drawing, forming a part thereof.

Figure 1 is a plan view of a repair buckle, and Fig. 2 is a side view of the same.

I claim,—

The ornamental design for a repair buckle, as shown.

In testimony whereof, I have affixed my signature in presence of two witnesses.

WALTER E. DEMPSEY.

Witnesses:

SADIE GATES,
A. A. DANIELSON.
